UNITED STATES PATENT OFFICE.

ELMER LEO EMERSON, OF MARSHALLTOWN, IOWA.

DOOR OPENER.

Application filed August 10, 1922. Serial No. 580,864.

To all whom it may concern:

Be it known that I, ELMER LEO EMERSON, a citizen of the United States, and a resident of Marshalltown, in the county of Marshall, 5 State of Iowa, have invented a certain new and useful Door Opener, of which the following is a specification.

My invention relates to that class of door openers that is especially desirable for use 10 in connection with garage doors, and which belongs to that class of door openers in which there is placed on the roadway approaching the garage and spaced apart from the garage a distance slightly greater than 15 the length of an automobile, a device for imparting movement to a door operating rod or shaft, and then on the garage doors there is a device to cause the door to open or close when actuated by the said device in 20 the roadway.

My object is to provide a door opener of this class of simple, durable and inexpensive construction, whereby the operator may upon approaching or leaving the garage drive 25 one of the car wheels upon a broad flat plate mounted on the roadway, and which plate when depressed by the weight of the car will operate to either open or close the garage door; and further in this connection to 30 cause said opening or closing movement to be accomplished without excessive strains on any of the parts, and without slanting the door.

A further object is to provide an automatic door latching device co-operating with 35 the door opening and closing device, and whereby when a car is approaching the garage, the door is automatically unlatched before the door opening device commences 40 its opening movement, and when a car is leaving the garage the door will be automatically unlatched from its open position before the door closing device commences its operative movement.

In this connection, it is a further object 45 to provide a door latching device of this character which, when the door is closed and latched and the car is inside the garage, the operator approaching the door from the outside may readily, quickly and easily unlatch 50 the door and swing it open by hand; and further in this connection it is my object to provide means whereby when the door is thus opened by hand, the latch may be manually adjusted so that the door will be latched 55 in its open position so that when driving the

car out of the garage the door cannot be swung closed by the wind.

A further object is to provide a device of the character described which may be 60 used as an attachment and applied to garage doors and drive ways leading to the garage without any material alterations in the doors or the drive ways and without forming a deep pit in the drive way, so that the device 65 may be quickly and easily installed by unskilled operators at a minimum of expense.

My invention consists in the construction, arrangement and combination of the various parts of the device, whereby the objects 70 contemplated are attained, as hereinafter more fully set forth, pointed out in my claims, and illustrated in the accompanying drawings, in which:

Figure 1 shows a top or plan view of two 75 hinged garage doors with my improved door opener applied thereto, the doors being shown in closed position. The dotted lines in said figure show the doors moved to their open position.

Figure 2 shows an enlarged, detail, side elevation of the device to be mounted in the roadway for imparting movement to the door operating rod.

Figure 3 shows an enlarged detail section- 85 al view illustrating the oil cushion device.

Figure 4 shows an enlarged detail elevation of the lower inner corner of the garage door to which the door operating rod is applied and illustrating the means for man- 90 ually operating the door latch device.

Figure 5 shows an enlarged detail view looking downwardly upon the garage door to which the door operating rod is attached, and illustrating the door in its closed position for the purpose of showing the means for manually operating the door latching device.

Figure 6 shows an enlarged detail edge view of the door to which the door operating rod is applied, and illustrating the latches on the inner and outer surface there- 100 of.

Figure 7 shows an enlarged detail front edge view of the door to which the operating rod is applied, and illustrating the latch for securing the same to a latch member on the operating rod.

Referring to the accompanying drawings, I have used the reference numeral 10 to 110 indicate the hinged garage door to which the operating rod is directly applied, and 11 the

hinged garage door on the opposite side of the door opening.

For causing the two doors to open and close in unison I have attached to the door 11 an arm 12 which is applied to the inner face of the door when in its closed position, and which extends inwardly from the door.

Pivottally connected to the bracket 12 is a rod 13 which is also pivottally connected 10 at 14 to the garage door 10. These parts are so shaped and proportioned that when the door 10 is moved from its closed position, as shown by solid lines in Figure 1, to its open position, as shown by dotted lines in 15 Figure 1, the door 11 will be swung to an open position, as shown by dotted lines in said figure.

In order to operate the doors by power 20 from an automobile approaching or leaving the garage, I place in the roadway at a distance spaced in front of the garage, a crank shaft 15 having two crank arms 16 thereon. These crank arms are so arranged relative to the shaft that when one of them is substantially horizontal, as shown in Figure 2, the other will extend upwardly and in a direction opposite from the first, as shown in Figure 2.

Formed on one end of the crank shaft 15 30 is a crank arm 17 and pivoted to the crank arm 17 is a door operating rod 18. For use in connection with each of the crank arms 16 I provide a broad flat operating plate 19. One of these plates is pivoted at 20 and extends 35 toward the garage doors, and its free end rests upon one of the crank arms 16. The plate 19 is pivottally supported at 21 at its end adjacent to the garage doors, and its free end extends away from the garage 40 and rests upon the other one of the cranks 16, as clearly shown in Figure 2.

In order to cushion the movement of the door opening and closing rod I preferably provide an oil cushion device indicated generally by the numeral 22, provided with a piston rod 23 which is attached to the crank arm 17. This oil cushion device is pivottally connected to a stationary support 24, and it comprises a cylinder having a piston 25 50 therein and a by-pass 26 communicating with the opposite ends of the cylinder. The operation of this oil cushion device is old and well known and it is familiar to those skilled in the art.

The end of the door operating rod 18 adjacent to the door 10 is preferably provided with a bend at 27 so arranged that the body of the rod may stand outside of the door when the door is in its open position, and 60 an end portion 28 of the push rod may extend under the door when it is in its closed position, as illustrated in Figure 5. I preferably cut away a portion of the door at its lower hinged corner, as shown in Figure 4, 65 to permit this rod to move under the corner

of the door. Then the inner end of the rod 18 is extended laterally at 29 parallel with the inner face of the door when the door is in its closed position, and then upwardly at 30, and this upwardly extended end is preferably provided with a roller 31.

Mounted upon the inner face of the door adjacent to the roller 31 is a bracket 32 having a horizontally extended plate 33 formed with a rectangular opening 34, and the roller 31 extends through this opening. The proportions of said parts being such that the roller may move to a limited extent in the annular opening 34 both in a direction parallel with the door and in a direction toward and from the door.

Mounted upon the inner face of the door 10 near its lower edge is a latch rod 35, the end thereof adjacent to the roller 31 being formed with an arm 36 extended above the 85 rod 35 and parallel therewith and inclined rearwardly away from the door, as illustrated in Figure 5. On the other end of the rod 35 is an arm 37 extending inwardly away from the door and attached to the gravity latch 38 pivoted to the door and designed to engage the latch member 39 fixed to a stationary support on the floor adjacent to the door.

The arrangement of these parts is such that when the roller 31 is moving toward the door, the rod 35 will be rocked in such a manner as to elevate the arm 37 and the latch 38 sufficiently to cause the latch to free itself from the latch member 39, and when the roller 31 is in its normal position, as shown in Figure 5, the latch will move by gravity to its lower position to engage the latch member 39, as shown in Figure 6.

Mounted upon the outer face of the door adjacent to its free edge is a gravity latch 40. This gravity latch is designed to coact with a latch member 41 which is secured by a clamp 42 to the door operating rod 18. This latch device 41 is so positioned upon the rod 18 that when the rod 18 is in its normal position and the door is swung open, the latch 40 will not engage the latch 41. This is illustrated in Figure 1 wherein the latch member 41 is shown in solid lines in such position that the latch member 42, which is shown by dotted lines in said figure, would not engage it, but when the rod 18 is moved to a slight extent forwardly away from the garage, then when the door is swung open the latch 40 will engage the latch member 41 and latch the door in an open position, as shown by dotted lines in Figure 1.

When an automobile is within the garage and it is desired to remove it, the operator 125 opens the garage doors by hand and when so doing it is at once desirable to latch the garage doors in an open position. For the purpose of conveniently and easily accomplishing this result I have provided on the inner 130

face of the door 10 near its lower hinged corner, a foot lever 43 to which is connected a link 44, and this link is pivotally connected to the upwardly extending part 30 of the door operating rod, as shown in Figure 4. The operation of this part of the device is as follows:

The operator swings the door 10 to a partly open position. He then presses upon 10 the foot lever 43 which causes the door operating rod 18 to move bodily in a direction away from the garage and far enough to bring the latch member 41 to position where the latch member 40 will engage it when the 15 door is fully open. This will latch the door in an open position and the door will be unlatched as soon as the door operating rod 18 is moved in an opposite direction or toward the door.

20 In practical operation and assuming that the device is in the position shown by solid lines in Figure 1 and an automobile is approaching, then if one of the front wheels of an automobile is run upon the broad flat 25 plate 19 at the left side, which applied a pressure downwardly upon the crank 16 and applies motion to the crank 17 in a direction tending to pull the door operating rod 18 away from the garage. This movement 30 will have the effect of first forcing the roller 31 against the arm 36 of the latch rod 35 in a forward direction or against the inner face of the door. The square opening 34 in the plate 33 permits this movement.

35 Obviously, the first action, therefore, of a pull upon the rod 18 will be to release the latch 38 and a further pull upon the rod 18 will operate to swing the doors open.

When the door 10 is swung to an open position, 40 the latch 40 on its outer face will engage the latch member 41 and latch the door in an open position, and this will be the result because the rod 18 is at its limit of movement away from the door, and hence the 45 latch member 41 will be in the path of the latch 40. During this movement the oil cushion will operate to cause the door to open slowly without slamming, and the weight of the automobile is sufficient to open 50 the door under any normal conditions. When the door is opened as shown by dotted lines in Figure 1, the rod 18 will be displaced laterally a slight distance, as shown by dotted lines, because its attachment to the 55 door is not in vertical alinement with the hinges of the door.

After the automobile has been driven through the open doors, the operator then closes the doors by hand. This is preferably 60 done by moving the rod 18 a slight distance in a direction toward the door, thus releasing the latch member 41 from the latch 40, and when the door 10 closes it will automatically latch because the latch 38 will engage the latch member 39 by gravity.

When it is desired to open the door by hand, the operator simply moves the rod 18 in a direction away from the door and this may be done by pressing the latch member 41 with his foot whereupon the latch 38 is released, and the door may be swung open.

If it is desired to latch the door in an open position, the operator may move the rod 18 in a direction away from the garage 70 by pressing upon the foot lever 43 until the latch member 41 is in position in the bend of the latch 40, then when the operator drives one of the car wheels over the inner one of the broad flat plates 19, the rod 18 will be pushed in a direction toward the 80 garage, thus first releasing the latch 40 and then causing the door to swing shut.

This movement of the upwardly extended end 30 of the rod 18 in two different directions relative to the plate 33 may be effected to a limited degree because the opening 34 in said plate 33 is substantially rectangular and larger than the diameter of the roller 31 so that sufficient movement of this roller 31 may take place for the purpose of operating the latches before the rod 18 commences to either open or close the door.

I claim as my invention:

1. In a device of the class described, the combination of a hinged door, a door operating rod, means for operating said rod, said rod having one end extended to a point adjacent to the inner side of the door when it is closed and then parallel with the inner face of the door and then upwardly, a bracket secured to the door and having an opening therein through which the upwardly extending end of the door operating rod is projected, said opening being large enough to permit a limited movement of the upwardly extending end of the operating rod both in a direction parallel with the inner face of the door and in a direction at right angles to the door when it is in its closed position, a door latch secured to the door, and means operated by the movement of the door operating rod within the bracket for releasing said latch, said parts being so arranged that after the latch has been released a continued pull upon the operating rod will swing the door open, a latch mounted on the outer surface of the door, and a coacting latch device secured to the door operating rod to co-operate therewith.

2. In a device of the class described, the combination of a hinged door, a door operating rod, means for operating said rod, said rod having one end extended to a point adjacent to the inner side of the door when it is closed and then parallel with the inner face of the door and then upwardly, a bracket secured to the door and having an opening therein through which the upwardly extending end of the door operating rod is projected, said opening being large enough to

permit a limited movement of the upwardly extending end of the operating rod both in a direction parallel with the inner face of the door and in a direction at right angles to the door when it is in its closed position, a door latch secured to the door, means operated by the movement of the door operating rod within the bracket for releasing said latch, said parts being so arranged that after the latch has been released a continued pull upon the operating rod will swing the door open, a latch mounted on the outer surface of the door, and a coacting latch device secured to the door operating rod to co-operate therewith, said latter latch device being so arranged that it may be released from the latch device on the outer surface of the door by a longitudinal movement of the door operating rod.

3. In a device of the class described, the combination of a hinged door, a door operating rod, means for operating said rod, said rod having one end extended to a point adjacent to the inner side of the door when it is closed and then parallel with the inner face of the door and then upwardly, a bracket secured to the door and having an opening therein through which the upwardly extending end of the door operating

rod is projected, said opening being large enough to permit a limited movement of the upwardly extending end of the operating rod both in a direction parallel with the inner face of the door and in a direction at right angles to the door when it is in its closed position, a door latch secured to the door, means operated by the movement of the door operating rod within the bracket for releasing said latch, said parts being so arranged that after the latch has been released a continued pull upon the operating rod will swing the door open, a latch mounted on the outer surface of the door, a coacting latch device secured to the door operating rod to co-operate therewith, said latter latch device being so arranged that it may be released from the latch device on the outer surface of the door by a longitudinal movement of the door operating rod, and a foot lever secured to the door and designed when depressed to move the door operating rod in a direction tending to place the latch device that is secured to the door operating rod in position to engage the latch device on the outer surface of the door when the door is swung open.

Des Moines, Iowa, July 29, 1922.

ELMER LEO EMERSON.
